UNITED STATES PATENT OFFICE

2,480,745

PISTON RING GROOVE CLEANER

William E. Law, Windsor, Calif.

Application May 17, 1948, Serial No. 27,474

2 Claims. (Cl. 15—104.01)

1

This invention relates to a piston ring groove scraping device.

It is an object of this invention to provide an improved piston ring groove scraping device of the kind to be more particularly described herein-after so constructed and arranged that it may be engaged in any piston ring groove of conventional size without the necessity of any manual adjustments on the tool.

Another object of this invention is to provide a tool of this kind by which the bottom and side edges of the groove may be scraped in a single operation.

Still another object of this invention is to provide a piston ring groove scraping tool which is substantially self-adjusting, being so formed that the scraping blades are resiliently biased into scraping engagement with the piston within the piston ring grooves.

A further object of this invention is to provide for the use of a single tool on cylinders of various sizes within the range of the tool, the tool being engageable in the various sized grooves of the various sized pistons without mechanical adjustment by the mechanic.

To the foregoing objects, and other which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a top plan view of a piston ring groove scraping tool constructed according to an embodiment of this invention.

Figure 2 is a transverse section taken on the line 2—2 of Figure 1.

Figure 3 is a side elevation of the tool removed from the piston shown in Figure 1.

Referring to the drawing, the numeral 10 designates generally an improved scraping tool for scraping and cleaning the piston ring grooves or pistons of automobiles and other combustion engines. The scraping tool 10 of my invention is formed of a single length of flat metal bent into a substantial U-shape to provide a handle 11 on which are supported scraping blades 12 and 14. The scraping blades 12 and 14 are fixed on one arm of the handle and a guide member 15 is fixed to or formed on an end of the other arm of the handle. The handle 11 being U-shaped is formed with a pair of substantially parallel arms 16 and

2

17 connected together at one end by a resilient bight portion 18. The resiliency of the connecting bight portion biases the arms 16 and 17 to a substantially parallel relation one to the other. The arm 16 is formed with an arcuate free end on which a support or guide 19 is formed. The scraping blades 12 and 14 are carried by the opposite arm 17 directly opposite from the guide member 19 for the purposes to be described hereinafter.

The arm 17 is bifurcated along its length to provide a pair of fingers 20 and 21 for supporting the scraping blades 12 and 14. The blades 12 and 14 are fixed to or formed on the free outer ends of the bifurcated arm 17 and may be formed as an integral part of the fingers. The fingers 20 and 21 are resiliently biased to a divergent relation at the ends thereof for urging apart the scraping blades 12 and 14. One of the fingers, 20, extends beyond the free end of the other finger 21 and the scraping blade 12 is supported on the lower side of the finger 20. The scraping blade 12 is then offset downwardly from the plane of the finger 20. The scraping blade 14 extends inwardly from the side edge of the finger 21 and is adapted to be disposed in the same plane as the scraping blade 12 when the fingers 20 and 21 are disposed in an overlying relation. The scraping blade 14 is adapted to follow directly behind the scraping blade 12 in certain positions of the fingers 20 and 21.

The guide member 19 is arcuate in configuration being fixed to or formed on the supporting member 15 and is in the same plane as the scraping blades 12 and 14 when they are disposed in an aligned position. As the scraping blade 12 is downwardly offset from the plane of the finger 20 to which it is attached, the scraping blade 14 may be disposed immediately behind the scraping blade 12 in the offset. The guide member 19 is substantially triangular in cross section so that it may be fitted into a piston ring groove of any size on the piston on which the tool 10 is being used.

The piston ring scraping tool 10 is formed in the manner described above so that it may be used for scraping the grooves of various sizes on the various sized pistons conventionally used in automobiles and other widely used automotive equipment. The pistons on the automobiles are provided with piston ring grooves of different widths for supporting the different piston rings as the oil scraping rings and the sealing rings. For this reason the expandable tool described above is provided for scraping all of the rings on any one piston. The scraping blades 12 and

14 are of a cross sectional thickness substantially the same as the smallest width of piston ring groove provided on the piston. As the piston ring grooves seldom vary more than twice the width of the smallest groove the expandible scraper will fit into and cleanly scrape any of the grooves between the smallest width and the largest or double width.

In the use and operation of this piston ring groove scraping tool the guide member support 15 is spread away from the scraping blades 12 and 14 and the guide member 19 is disposed in one of the grooves of the piston P. The fingers 20 and 21 are then pressed together to dispose the scraper blades 12 and 14 in following relation and the scraper blades are then engaged in the piston ring groove opposite from the guide 19. The resiliency of the fingers 20 and 21 will spread the scraper blades 12 and 14 apart so that one of them, as 12, will engage the upper surface of the groove and the other, as 14, will engage the lower surface of the groove and the inner edges of both of the blades will engage the bottom of the groove. The tool 10 may then be rotated relative to the piston P and the cutting edges of the blades will scrape the carbon and other deposits from the grooves. The extreme inner ends of the scraping blades 12 and 14 are inclined at an angle relative to the length of the blades so that a cutting point is provided on each of the blades. This angular formation on the end of the blades provides a beveled edge as 22 so that the blades may be used for scraping the oil ring groove which is provided with openings through the walls of the piston. The cutting points of the blades will engage in the openings through the wall and at this time the tool 10 may be reversed in the direction of rotation for freeing the scraping blades so that these openings are not damaged and that no damage is caused to the terminal ends of the scraping blades. When the tool is used for the narrow grooves the scraping blades will be disposed in aligned position relative to each other so that a total width no greater than the width of the groove being operated upon is formed. Also, where the grooves are relatively narrow, the scraping blades may be engaged in adjacent grooves for scraping two grooves at one time.

I claim:

1. A piston ring groove scraping tool comprising a guide arm, a scraper arm, and means resiliently connecting said arms together, said scraper arm including a pair of resilient fingers diverging in a plane substantially perpendicular to the plane passing through said guide arm and said scraper arm, one of said fingers being formed with an offset portion at the free end thereof adapted to overlie the free end of the other of said pair of fingers, and a pair of scraper blades secured to said offset portion and to said latter free end respectively whereby said pair of blades may be disposed in a piston groove in alignment relative to each other.

2. A piston ring groove scraping tool comprising a guide arm having an arcuate guide member secured on one end thereof, a scraper arm, and means resiliently connecting said arms together, said scraper arm including a pair of resilient fingers diverging in a plane substantially perpendicular to the plane passing through said guide arm and said scraper arm, one of said fingers extending longitudinally beyond the other 25 of said fingers and having an offset end portion adapted to overlie the free end of the other of said pair of fingers, and a pair of scraper blades carried by said offset portion and said free end respectively, said scraper blades being positioned 30 equidistant from a radial line extending from said arcuate guide member whereby said pair of blades may be disposed in a piston groove in trailing alignment relative to each other.

WILLIAM E. LAW.
